ENGINE CONTROL APPARATUS

Charles I. McNeil, Bloomfield, N. J., assignor, by
mesne assignments, to Eclipse Aviation Cor-
poration, East Orange, N. J., a corporation of
New Jersey

Application September 13, 1932, Serial No. 633,000

5 Claims. (Cl. 123—103)

This invention relates to engine control apparatus and particularly to means for automatically controlling the supply of fuel to an internal combustion engine.

5 An object of the invention is to provide means for controlling the automatic operation of the throttle valve of an internal combustion engine in accordance with the pressure prevailing in some chamber, such as the intake manifold, 10 through which the fuel charge passes on its way to the combustion chamber or chambers of the engine.

Another object of the invention is to provide combined pressure and temperature responsive 15 means for controlling the setting of the engine throttle valve.

A further object of the invention is to provide combined thermo-electric and electro-magnetic means for controlling the setting of the engine 20 throttle valve.

25 A further object of the invention is to provide means operative after the lapse of a predetermined time interval, measured from the time of closure of the engine ignition circuit, for varying the setting of the engine throttle valve.

These and other objects and advantages to be derived from the use of the invention herein disclosed involve the inter-relation and relative 30 functions of the parts, and will become apparent upon an inspection of the following specification and the accompanying drawing, wherein the preferred embodiment of the invention is disclosed. It is to be understood, however, that the drawing is for the purpose of illustration only 35 and is not designed as a definition of the limits of the invention, reference being had for such purpose to the appended claims.

The drawing shows a schematic representation 40 of the novel instrumentalities in which the present invention may be embodied.

In the drawing, the invention is shown applied to a throttle valve 6 located in the carburetor or other conduit 1 joined by a flange 8 to the intake manifold 9 of an internal combustion engine (not completely shown) the throttle valve being shown as of the usual type involving a circular disc mounted on the pin 11 adapted to be oscillated by reason of the connection therewith of an arm 12 which is attached by a pin and slot 45 connection as indicated at 25, to the usual accelerator link 13; the arm 12 being normally held against a stop 16 by the action of a tension spring 17 anchored to the conduit 1 as indicated at 18 and connected to a projection of the arm 12, as 50 indicated at 19.

The combined pressure and temperature responsive means for moving the throttle against the tension of spring 17, preferably takes the form of a heating coil 22 connected with an electrical circuit leading from a suitable source of 5 current, such as a battery 23, and closable by operation of any suitable switch means, such as indicated at 24, constituting also the means for closing the circuit to the ignition system, only one lead 26 of which is indicated in the drawing, 10 as the ignition system per se forms no part of the present invention. A suitable resistance coil 27, may, if desired, be interposed between the leads 28 and 29 connecting the battery with the heating coil 22, said resistance being shown as in 15 shunt with the winding 31 of an electro-magnetic device herein shown as a solenoid having a magnetizable core or plunger 32 provided with a fixed collar 20 adapted to contact with a stop member 21 to limit the movement of valve 6 20 when the solenoid is energized. The outer end of the plunger is apertured as indicated at 33 for reception of one end of a flexible connection herein shown as a cable 14 with its opposite end attached to the arm 12 as indicated at 15. 25

As shown the heating coil 22 is wound about a bi-metallic strip 36 secured to, and insulated from, as indicated at 37, a bracket 38 extending from a cup-shaped element 39 which, together with the flexible diaphragm 40, forms a sealed 30 chamber permanently in communication with the intake manifold 9 by virtue of the interconnecting conduit 41. As shown, the circuits to both the winding 31 and heating coil 22 pass by way of the cup-shaped element 39 to the conductor 47 leading to the ground 48, the other side of the battery being also grounded as indicated at 49. At the lower end of the bi-metallic strip 36 there is provided a current conducting contact 51, the flexure of the strip being such that 40 under normal conditions (that is, with no current flowing through the heating coil 22) contact 51 is in engagement with a corresponding contact 53 mounted at the center of the flexible diaphragm 40. Preferably the setting is such that 45 the diaphragm movement is not enough, in itself, to open the contacts, and the arm 36 is preferably so arranged that it follows the diaphragm and thus maintains the circuit closed until the current has been flowing through the 50 heating coil for a given period of time.

Having thus described the parts entering into the preferred embodiment of the invention shown, the operation thereof will be seen to be 55 as follows:

Upon closing the ignition switch 24 current flows from the battery 23 to line 28 and the resistor 27 and heating coil 22, which slowly heats the bi-metallic arm 36 carrying contact 51. At the same time current flows through traction solenoid 31, lead 35, arm 36, contacts 51, 53 and diaphragm 40 to ground, completing the battery circuit. This current passing through the solenoid creates a magnetic pull which attracts plunger 32 and moves it to the left as viewed in the drawing (until collar 20 abuts stop member 21) and opens the throttle sufficiently to permit the induction into the engine, of a sufficient fuel charge for starting purposes. The throttle then remains in this position until contacts 51 and 53 are separated by the heat-induced flexure of arm 36, aided by the increase in the degree of intake manifold vacuum which occurs as soon as the engine starts. At any time thereafter when the manifold vacuum falls below some predetermined point (such as would happen immediately preceding a stall) the resulting increased pressure on the diaphragm will cause the contact 53 to move toward the left as shown in the drawing, to again close the circuit through arm 36, and the solenoid 31 to open the throttle and prevent the stall from taking place.

There is thus disclosed a novel engine control mechanism whereby the supply of fuel under the control of combined pressure and temperature responsive means is so inter-related as to function properly to vary the setting of the throttle valve automatically as the varying conditions require.

As above explained, the mechanical construction of the individual elements controlled by the novel mechanism herein disclosed may vary as desired, as may also the precise method of electrically and electro-magnetically inter-relating the controls therefor, provided one or more of the essential features of the system are retained. Likewise other changes, substitutions, and omissions may be made within the scope of the broadest of the appended claims.

What is claimed is:

1. In combination with an internal combustion engine having a fuel intake conduit and a variable volume chamber in constant communication therewith, a flexible diaphragm forming a part of said chamber, means responsive to a predetermined temperature rise and coincident movement of said diaphragm for varying the effective cross-sectional area of said intake conduit and

thereby controlling the amount of fuel drawn therethrough, said last named means comprising a throttle valve and an electro-magnetic device for shifting said throttle valve, and means mounted on said diaphragm for controlling the energization of said electro-magnetic device.

2. In combination with an internal combustion engine having a fuel intake conduit, a throttle valve therein, electro-magnetic means for shifting said throttle valve, means responsive to the closing of the ignition circuit of the engine for initially energizing said electro-magnetic means, and pressure responsive means operative only after the lapse of a predetermined time interval following such initial energization for de-energizing said electro-magnetic means.

3. In combination with an internal combustion engine having a fuel intake conduit, a throttle valve therein, electro-magnetic means for shifting said throttle valve, means responsive to the closing of the ignition circuit of the engine for initially energizing said electro-magnetic means, and combined temperature and pressure responsive means for de-energizing said electro-magnetic means.

4. In combination with an internal combustion engine having an ignition circuit, a fuel intake conduit, a throttle valve therein, and a variable volume chamber, means responsive to a drop in intake conduit pressure to decrease the volume of said chamber, electromagnetic means responsive to closure of the ignition circuit to exert an actuating pull on said throttle valve, and means for de-energizing said electromagnetic means after the ignition circuit has been closed for a definite period, said de-energizing means being effective only in the event that said first named means has operated to decrease the chamber volume.

5. In combination with an internal combustion engine having an ignition circuit, a fuel intake conduit, a throttle valve therein, and a variable volume chamber, means responsive to a drop in intake conduit pressure to decrease the volume of said chamber, means responsive to closure of the ignition circuit to exert an actuating pull on said throttle valve, and means for releasing said actuating pull after the ignition circuit has been closed for a definite period, said releasing means being effective only in the event that said first named means has operated to decrease the chamber volume.

CHARLES I. MCNEIL.
